DATA COMMUNICATIONS TERMINAL AND INSPECTOR'S STATION

Walter W. Wiebe, 1915 Alexander Road,
Raleigh, N.C. 27608

Filed Apr. 25, 1974, Ser. No. 464,267

Term of patent 14 years

Int. Cl. D14—02

U.S. Cl. D26—5 C

FIG. 1

FIG. 2

FIG. 3

FIG. 4

FIG. 5

FIG. 1 is a perspective view taken from the front and right side of a data communications and inspector's terminal embodying my new design.

FIG. 2 is a front elevational view thereof.

FIG. 3 is a right side elevational view thereof, shown partially in cross-section.

FIG. 4 is a top plan view thereof.

FIG. 5 is a rear elevational view thereof.

I claim:

The ornamental design for a data communications terminal and inspector's station, substantially as shown and described.
